UNITED STATES PATENT OFFICE

ALONZO LINTON BAUSMAN, OF SPRINGFIELD, MASSACHUSETTS, ASSIGNOR TO NATIONAL EQUIPMENT COMPANY, OF SPRINGFIELD, MASSACHUSETTS, A CORPORATION OF MASSACHUSETTS

DELIVERY APPARATUS FOR CONFECTIONERY MACHINES

Application filed October 7, 1927. Serial No. 224,668.

This invention relates to improvements in confection making machines and has particular reference to the so-called delivery apparatus therefor.

Such apparatus may take a wide variety of forms but these various forms may be resolved into two distinct types. In one type, the delivery apparatus consists of an endless conveyer of considerable length which usually, although not necessarily, travels through a so-called cold box, whereby the confections, such for example as coated confections, are carried by the belt until their coatings have cooled or hardened. In this type of apparatus, the confections, when they reach the delivery point are ready for packing. In the other type, the confections are delivered upon individual plaques, which are usually although not necessarily, pieces of waxed paper, and provisions are made for successively presenting the plaques into confection receiving relation with the coating or other confection making machine. The plaques, after having been loaded with confections, are removed and disposed of in various ways. Sometimes they are placed on trays which are transferred manually or automatically to the conveyer of a separate cooling apparatus. In other cases, the plaques are stacked in racks, usually in a cold room. In some cases, however, where air drying will suffice to harden the confections, as for example with caramel, the plaques are stacked in a room at ordinary temperature. With the second type of apparatus, the confections when removed from the delivery apparatus, require further treatment before they are ready for packing. In both types of apparatus it has been the practice to deposit the confections on a waxed or similar surface so that the confections will not adhere thereto. In the first type of apparatus the endless belt has been made of waxed or similar paper, oil cloth and the like and in the second type the plaques themselves are formed of the above or similar materials.

While the above materials suffice for the ordinary work of confection-making machines, they are not suitable for all kinds of confections. Sticky substances, of which caramel is a good example, will adhere to the

usual plaques or equivalent confection-receiving members of the delivery apparatus of confection making machines.

The problem of this invention is to provide means for automatically treating and preparing the receiving surface of a confection receiving member of the delivery apparatus of a confection making machine, whether for coating purposes or otherwise, so as to render it suitable for use with confections having coatings or outer surfaces of a sticky substance, such as caramel for example.

In carrying out this object, means are provided for dusting the confection-receiving surface with flour or the like before it reaches the delivery end of the coating machine and in many cases the confection receiving member, in order to reach this position has to travel upside down so that the flour dusted surface is lowermost. This gives rise to another problem which is to hold the flour in place on the confection receiving surface from the time when it is applied until the surface moves into position to receive the confections.

It is another object of the invention to provide means for coating the confection receiving surfaces with a greasy or oily substance prior to the time of application of the flour. This film of oil or grease tends to hold the particles of flour together and make the layer of flour coherent.

Another object of the invention is to provide means for working the flour into the oil or grease, the better to secure coherency of the flour particles. In carrying out this object, I prefer to provide a belt which underlies and moves in contact with the confection receiving surface or surfaces while they are disposed downwardly. This belt not only serves to hold the flour against the surface but it actively serves to work the flour into the oil or grease. The result may be secured in various ways. One way is to make the belt press the flour into the grease. Another way is to make the belt travel at a slightly different speed than the confection receiving surface, whereby the belt will serve to rub the flour into the grease. By preference, the

belt is made to accomplish the result in both ways.

Other objects and advantages will appear in the following description and will be pointed out in the appended claims.

The invention will be disclosed with reference to the accompanying drawings, in which:—

Fig. 1 is a side elevational view of a delivery apparatus embodying the invention;

Fig. 2 is a fragmentary sectional elevational view, drawn to a much larger scale and illustrating the manner in which the flour is applied and worked into the confection receiving plaques;

Fig. 3 is a fragmentary sectional elevational view of the confection receiving member, showing a plaque moving into confection receiving position;

Fig. 4 is a view taken on the line 4—4 of Fig. 1 and shows a device for applying flour or the like to the plaques;

Fig. 5 is an end view of the flour applying device taken from a direction opposite to that in which Fig. 1 is taken;

Fig. 6 is a cross sectional view taken on the line 6—6 of Fig. 4;

Fig. 7 is a view taken on the line 7—7 of Fig. 1; and

Fig. 8 is a diagrammatical view illustrative of a modification of the invention.

Referring to these drawings, A represents a portion of a confection coating machine, which may be of any suitable type, and b is the coating machine belt, which carries the coated confections, such as c. The confections c pass off belt b onto plaques p, of waxed paper or the like. These plaques may be held to a delivery belt 10 in any suitable manner which will permit quick and convenient application of the plaques to, or the removal of them from belt 10. As shown, each plaque is held at one end beneath a flap f. A series of such flaps are secured at suitable intervals to belt 10. The arrangement is like that disclosed in my prior U. S. Letters Patent No. 927,928, granted July 13, 1909, to which reference is made for a more complete disclosure. Since the type of delivery apparatus, which has been chosen by way of illustrative example to show the background for this invention, is fully disclosed in said patent, a brief description of it will suffice for present purposes. The belt 10, in its upper stretch of travel runs over and is supported by a table 11 and at one end is trained around the rounded edge of a thin bar 12 (Fig. 3) secured to table 11. At its other end, the belt 10 is trained around a driving roll 13, which is mounted at its ends in a pedestal 14 and driven by a worm 16 and worm gear 15 from a shaft 17. Table 11 is supported at one end from pedestal 14 and at the other end by legs 18 and at an intermediate point by legs 19. Shaft 17 is driven by a chain 20 from a shaft 21, which in turn

is driven from a power shaft of the coating machine A in the usual manner.

Adjacent the driving roll 13 is a similar driving roll 22 for a canvas belt 23, which is of a width at least equal to that of plaques p. Roll 22 is driven by a worm 25 and worm gear 24 from shaft 17. The bearings for rolls 13 and 22 are mounted in pedestal 14 for longitudinal adjustment and can be moved by turning the screws 26 and 27, respectively. The belt 23 is trained between the roll 22 and a small roll 28 (Fig. 3) located adjacent but below plate 12. The upper stretch of belt 23 passes partially around and beneath roll 13 so as to press against the plaques p carried by the belt 10. Similarly roll 28 causes the upper stretch of belt 23 to be pressed against the belt 10 and the plaques carried thereby. By adjusting the screws 26 and 27 the two adjacent stretches of belts 10 and 23 may be caused to move in contiguous relation and the belt 23 caused to press against belt 10. The intermediate idler rolls 29 merely support the belts and prevent them from sagging. The belt 23 is preferably driven from roll 22 at a slightly different speed than belt 10. Belt 23 naturally turns roll 28 and the latter carries a pinion 30, which drives through a gear 31 the two pinions 32, which in turn drive the usual plaque stretching rolls 33. It will not be necessary to consider the action of these rolls as it has been disclosed in the aforesaid patent and has no special cooperation with the elements of this invention. So also the manner in which the plaques are held to belt 10 and carried between the latter and belt 23 in their return travel is sufficiently disclosed in said patent.

Overlying the upper stretch of belt 10 and adjacent driving roll 13 is a hopper 35, which contains a supply of flour or the like and has associated therewith some suitable means for distributing the flour in a substantially even layer over the plaques p shortly before they start to turn around the roll and commence their return stretch of travel. Located a little ahead of this hopper is a casing 36, supported by and above table 11, through which casing the plaques p are caused to travel and receive a coating of oil or grease, applied in any suitable manner. The plaques p, when loaded with freshly coated confections, travel towards the left as viewed in Fig. 1, and are removed, as soon as possible and considerably before they reach casing 36. Fresh plaques are placed on belt 10 to replace those removed, and this operation also is effected early enough in the upper stretch of travel of belt 10 so that fresh and unladen plaques only pass through casing 36.

In Fig. 7, an exemplary apparatus for applying the oil or grease is shown. As there indicated, two spray nozzles 37 are provided, one at each end of casing 36, and these nozzles are arranged to throw a spray of oil or the

like into casing 36 and upon plaques *p* in such a manner as to cover all parts thereof. The oil is, or may be, contained in reservoirs 38, one fixed to each side of table 11 and the nozzles are mounted on these reservoirs and supplied therefrom by tubes 39. Compressed air, for example, may be admitted through pipes 40 into the nozzles to lift the oil up tubes 39 and force it from the nozzles in the form of a spray. Troughs 41, one secured to the inner surface of each side wall of casing 36, near the bottom thereof, are intended to catch excess oil and deliver it at opposite ends into side troughs 42, from which it may be drained into any suitable receptacle. The oil spraying device is, or may be, similar in general form to that used for applying paint and is given merely by way of an illustrative example of one suitable means for accomplishing the desired function.

In Figs. 4, 5 and 6 I have shown an exemplary apparatus for applying flour to the plaques. The hopper 35, heretofore referred to, is supported as indicated in Figs. 1 and 4, from an angle iron frame 43 and extends across and above the level of the upper stretch of belt 10. This hopper has an outlet 44 in its bottom wall through which flour falls and lodges upon a reciprocating screen 45. This screen is mounted to reciprocate in a direction crosswise of the travel of belt 10 and slides on angle iron guides 46. The screen is reciprocated by two connecting rods 47, arranged one on each side thereof, which rods are connected to crank pins 48, fixed one to each end of a shaft 49, mounted in bearings on the back wall of hopper 35. Extending through the hopper and mounted for sliding movement in the end walls thereof, is a shaft 50 which centrally overlies the outlet 44. One end of shaft 50 has a pin and slot connection with the upper end of a lever 51, which is fixed to a shaft 52, rotatably supported from the back wall of hopper 35 and above shaft 49. Also fixed to shaft 52 is a lever 53 having two depending arms which straddle an eccentric 54, fixed on shaft 49. The latter is driven by a chain 55 from a shaft, which is mounted in bearings fixed to the rear legs of pedestal 14 and lies directly behind shaft 20, as viewed in Fig. 1, being connected to shaft 20 by a chain 56.

Referring back to Figs. 4 and 5, it will be seen that screen 45 and shaft 50 are moved back and forth in parallel paths. Screen 45 is intended to distribute the flour over the plaque by a sifting action but in order to make it as effective as possible, it is desirable to control the discharge of flour from the outlet 44 of hopper 35 so that no large accumulations of flour will lodge on the screen. To effect this result a coil spring 57 (Fig. 6) is secured to and below shaft 50 and the lower periphery of the spring overlies the outlet 44 in closely adjacent relation therewith. As

shown, an angle iron 58 is adjustably connected at intervals throughout its length by screws 59 to shaft 50. The legs of the angle iron diverge downwardly and outwardly from the vertical center line of the hopper and these legs form a seat to receive the spring. A half round bar 60 is passed through the spring and the screws 59 thread into bar 60, whereby the upper peripheral portion of the spring is clamped between this bar and angle iron 58. The ends of the spring (see Fig. 4) preferably taper upwardly away from the outlet. Unless the ends of the spring are tapered, the flow of flour through outlet 44 is not uniform throughout its length. Less flour would flow from the ends of outlet 44 than at intermediate points. The spring with its many coils, functions to restrict the outlet and retard the flow of flour. The spring, being constantly reciprocated, shakes down flour in substantially controlled and regulated quantities and causes the supply to screen 45 to be distributed substantially evenly thereover.

In operation, the fresh and unladen plaques *p*, which are placed on belt 10 at an intermediate point in its upper stretch of travel, move to the left, as viewed in Fig. 1, and first pass through casing 36 and thereafter pass in under the reciprocating screen 45. Thus, each plaque is first given a coating of any suitable oily or greasy substance and thereafter this coating is covered with flour, which is dusted and distributed thereon by the reciprocating screen. Shortly after these two coatings have been applied to a plaque, it bends around roll 13 and commences that stretch of travel which leads to the confection coating machine. During that stretch of travel the flour dusted surface of each plaque lies downward and the flour would, to a certain extent, fall from the plaque unless means were provided to prevent this action. Such means, in the example illustrated, take the form of the belt 23, which as will be seen from Fig. 2, comes into play very shortly after the application of the layer of flour and presses the flour against the plaque and forces it into intimate contact with the oily or greasy substance. The flour soaks up some of the greasy substance and the result is to make the loose particles of the flour stick together to some extent and render the layer coherent. Also, the difference in speed of belts 10 and 23 produces a rolling of the flour particles, which serves to rub them into the grease and increase the desired effect. Thus, the flour is worked into the grease by pressing and rubbing and this is effected almost immediately after belt 23 comes in contact with the flour, i. e., as it bends around under roll 13. The described action, as effected at this one location might under some conditions suffice, in which case belt 23 would not need to underlie so much of

the lower stretch of belt 10. However, the illustrated arrangement is desirable if for no other reason than to prevent occasional loose particles of flour from falling to the floor. 5 As a matter of fact, the pressing and rubbing action is continued over nearly all of the lower stretch of travel of belt 10 as I deem it desirable to secure the best results. The aim is to get the flour worked into the grease to a 10 sufficient extent so that the flour will adhere to the plaque, when it is turned around the rounded edge of plate 12 and brought into confection receiving relation with the coating machine A, i. e., into the initial part of its 15 upper stretch of travel. It is not desired to have the layer of flour completely oil soaked, or completely wet through, and care must be exercised (by regulation of the amount of oil coating, the amount of flour 20 coating and the amount of pressing and rubbing effected by belt 23), to get the desired results. The confections *c* are delivered from belt *b*, and transferred to the plaques in the usual manner, except that the confections 25 rest upon a layer of flour or other like material, to which the sticky coating, such as caramel or the like, will not adhere. The confection laden plaques are removed from belt 10 as soon as possible and replaced with 30 fresh plaques which are then successively treated in the manner above described.

It will be apparent that in lieu of the series 35 of plaques, a single endless plaque could be substituted, as indicated in Fig. 8. The treatment of this endless plaque could be substantially the same except that it might be necessary to provide a scraper (conventionally indicated at 70) to remove the coating of flour from the plaque, after the confections have 40 been removed and before the oil and flour applying devices are reached. In this figure, the endless plaque, which is designated 71, receives the confections as before from coating machine A and carries them through a 45 cold box 72, whereby the confections are cooled. The cooled confections are picked off plaque 71 after it emerges from the cold box 72 and before the scraper 70 is reached.

While the invention has been disclosed in 50 connection with a coating machine, it will be obvious that the invention is applicable to other classes of confection making machines and is not dependent on, or restricted to, the particular type of machine illustrated.

55 The invention has been disclosed herein, in an embodiment at present preferred, for illustrative purposes but the scope of the invention is defined by the appended claims rather than by the foregoing description.

60 What I claim is:

1. The combination with a confectionery machine adapted to deliver confections having sticky surfaces, of a member movable in such relation to said machine as to receive 65 confections therefrom, means for distribut-

ing flour or the like over the confection receiving surface of said member, and means for holding the applied flour in place on said member until confections have been delivered thereon from said machine. 70

2. The combination with a confectionery machine adapted to deliver confections having sticky surfaces, of a member movable in such relation to said machine as to receive confections therefrom, means for applying a greasy substance to the confection receiving surface of said member, and means for distributing flour or the like over the greased surface of said member. 75

3. The combination with a confectionery machine adapted to deliver confections having sticky surfaces, of a member movable in such relation to said machine as to receive confections therefrom, means for applying a greasy substance to the confection receiving surface of said member, means for distributing flour or the like over the greased surface of said member and means for working the flour into the greasy coating. 80

4. The combination with a confectionery machine and means for successively presenting plaques into confection-receiving relation therewith, of means for preparing the plaques to receive the confections, comprising means for coating the confection receiving surface of each plaque with a greasy substance, and means for distributing flour or the like over said greasy coating. 85

5. The combination with a confectionery machine and means for successively presenting plaques into confection-receiving relation therewith, of means for preparing the plaques to receive the confections, comprising means for coating the confection receiving surface of each plaque with a greasy substance, means for distributing flour or the like over said greasy coating, and means for packing the flour into the greasy coating to hold the flour in place on the plaque. 90

6. The combination with a confectionery machine and means for successively presenting plaques into confection-receiving relation therewith, of means for preparing the plaques to receive the confections, comprising means for coating the confection receiving surface of the plaque with a greasy substance, means for distributing flour or the like over said greasy coating, and means for rubbing the flour into the greasy coating to hold the flour in place on the plaque. 105

7. In a confectionery machine, of the type wherein confections are delivered to plaques carried by an endless belt while said belt is moving in its upper stretch of travel and the loaded plaques are removed from said belt and replaced with empty plaques during said stretch of travel, the combination with such belt and plaques of means for successively applying to each empty plaque a greasy coating, means for distributing flour or the like 110

over said coating, and a member movable along the lower stretch of said belt and in the same direction and adapted to hold the flour from falling from the plaques while the latter are travelling in the inverted relation.

8. In a confectionery machine, of the type wherein confections are delivered to plaques carried by an endless belt while said belt is moving in its upper stretch of travel and the loaded plaques are removed from said belt and replaced with empty plaques during said stretch of travel, the combination with such belt and plaques of means for successively applying to each empty plaque a greasy coating, means for distributing flour or the like over said coating, and a member movable along the lower stretch of said belt and in the same direction, said member adapted to hold the flour from falling from the plaques while the latter are travelling in inverted relation and to press the flour into said greasy coating.

9. In a confectionery machine, of the type wherein confections are delivered to plaques carried by an endless belt while said belt is moving in its upper stretch of travel and the loaded plaques are removed from said belt and replaced with empty plaques during said stretch of travel, the combination with such belt and plaques of means for successively applying to each empty plaque a greasy coating, means for distributing flour or the like over said coating, and a member movable along the lower stretch of said belt and in the same direction, said member adapted to hold the flour from falling from the plaques while the latter are travelling in inverted relation, and being movable at a different speed than said belt, whereby it causes the flour to be rubbed into the greasy coating.

In testimony whereof I have affixed my signature.

ALONZO LINTON BAUSMAN.
